Jas. A. St John. Manager.

UNITED STATES PATENT OFFICE.

JAMES A. ST. JOHN, OF ST. LOUIS, MISSOURI.

DESIGN FOR MOVABLE TYPE.

SPECIFICATION forming part of Design No. 12,520, dated October 11, 1881.

Application filed August 24, 1881. Term of patent 7 years.

To all whom it may concern:

Be it known that I, JAMES A. ST. JOHN, a subject of the Queen of Great Britain, residing in the city of St. Louis, Missouri, have invented and produced a new and original Design for Movable Types, of which the following is a specification, reference being had to the accompanying impression, forming part thereof.

The present invention is an improvement in what is termed "Old-Style Type."

The feature characterizing the present font is the lateral extension of the type—that is, the face of the type, in place of being lean or narrow in proportion to its height, as hitherto,

is broad in proportion to its height, as shown 15 in the accompanying fac-simile.

The other features of the type, such as the outline and shading, are similar to those of the ordinary old-style type, saving as modified by the extension feature in question. 20

I claim—

The design for old-style movable type herein shown and described, the same consisting in the extended face.

JAMES A. ST. JOHN.
